(57) **CLAIM**

The ornamental design for a collapsible drinking container, as shown and described.

DESCRIPTION

FIG. 1 is a top perspective view of a collapsible drinking container showing my new design;

FIG. 2 is a front end view of the collapsible drinking container of FIG. 1;

FIG. 3 is a right side elevation view of the collapsible drinking container of FIG. 1;

FIG. 4 is a left side elevation view of the collapsible drinking container of FIG. 1;

FIG. 5 is a rear end view of the collapsible drinking container of FIG. 1;

FIG. 6 is a top plan view of the collapsible drinking container of FIG. 1; the top plan view of the collapsible drinking container in a collapsed state being identical to the top plan view shown in FIG. 6;

FIG. 7 is a bottom plan view of the collapsible drinking container of FIG. 1;

FIG. 8 is a bottom perspective view of the collapsible drinking container of FIG. 1;

FIG. 9 is a bottom perspective view of the collapsible drinking container of FIG. 1 in a collapsed state;

FIG. 10 is a front end view of the collapsible drinking container of FIG. 1 in a collapsed state;

FIG. 11 is a right side elevation view of the collapsible drinking container of FIG. 1 in a collapsed state;

FIG. 12 is a left side elevation view of the collapsible drinking container of FIG. 1 in a collapsed state;

FIG. 13 is a rear end view of the collapsible drinking container of FIG. 1 in a collapsed state; and,

FIG. 14 is a bottom plan view of the collapsible drinking container of FIG. 1 in a collapsed state.

The shade lines in the Figures show contour and not surface ornamentation.

The broken lines shown in the Figures show portions of the collapsible drinking container that form no part of the claimed design.

1 Claim, 11 Drawing Sheets
